UNITED STATES PATENT OFFICE.

WILLIAM L. OSBORNE, OF CHICAGO, ILLINOIS.

DESIGN FOR A HAND-WHEEL FOR VALVES.

42,770.

Specification for Design.

Patented July 9, 1912.

Application filed February 10, 1912. Serial No. 676,829. Term of patent 7 years.

To all whom it may concern:

Be it known that I, WILLIAM L. OSBORNE, a citizen of the United States, residing at Chicago, in the county of Cook and State of Illinois, have invented a new, original, and ornamental Design for a Hand-Wheel for Valves, of which the following is a specification, reference being had to the accompanying drawings, forming part thereof.

In the drawings:—Figure 1 is a plan

view, and Fig. 2 is a side elevation of a hand wheel for valves showing my new design.

I claim:

The ornamental design for a hand wheel for valves, as shown.

WILLIAM L. OSBORNE.

Witnesses:

G. E. DOWLE,
W. L. HALL.
